UNITED STATES PATENT OFFICE.

WILLIAM C. WILLIAMSON AND JOHN D. WILLIAMSON, JR., OF PHILADELPHIA, PENNSYLVANIA, ASSIGNORS TO THE WILLIAMSON BROTHERS COMPANY, OF SAME PLACE.

TILLER STEERING-GEAR FOR VESSELS.

SPECIFICATION forming part of Letters Patent No. 653,601, dated July 10, 1900.

Application filed May 3, 1900. Serial No. 15,403. (No model.)

To all whom it may concern:

Be it known that we, WILLIAM C. WILLIAMSON and JOHN D. WILLIAMSON, Jr., citizens of the United States, and residents of 5 Philadelphia, Pennsylvania, have invented certain Improvements in Tiller Steering-Gears for Vessels, of which the following is a specification.

The object of our invention is to improve 10 the construction of power tiller steering-gears for vessels, and this object we attain by, first, mounting the tiller-shifting engines on a fixed foundation, and, second, providing means for taking up the shock due to the 15 striking of the waves against the rudder, thus relieving the tiller-operating mechanism from these jars.

In the accompanying drawings, Figure 1 is 20 a plan view of our improved power tiller steering-gear. Fig. 2 is a section on the line 2 2, Fig. 1. Fig. 3 is an enlarged sectional view of one of the buffers, and Figs. 4 and 5 are views of modifications.

A is the deck of the vessel.

25 B is the rudder-post, to which the tiller D is secured in the present instance, as shown clearly in Fig. 2. Carried by the outer end of the tiller is a vertical shaft d, on which is a pinion d'. The teeth of this pinion engage 30 with the teeth of a segmental rack E, as shown in Fig. 1. On the shaft d is a worm-wheel d², with which meshes a worm c on the shaft C. On the opposite end of this shaft is a bevel-wheel c'. The shaft C is mounted in 35 bearings f, secured to the tiller D.

G is a vertical driving-shaft in line with the rudder-post B. On this driving-shaft is a bevel-pinion g, which meshes with the bevel-pinion c' of the shaft C. The driving-shaft 40 G in the present instance has a crank g'.

H II are the engines or motors. In the present instance we have shown steam-engines having connecting-rods h h coupled to the crank of the driving-shaft G. h' represents the steam-chests of the engines, and any suitable valve mechanism may be used on the engines. The type of engine may be varied without departing from our invention. For instance, in some cases other motive power 45 than steam may be employed, as will be read-

ily understood. The engines are mounted on a suitable foundation F, which in the present instance incloses both the tiller-head and the bevel driving-gears.

The worm-wheel d² is connected to the shaft 55 D by any suitable coupling d³ of the ordinary form used in this type of steering-gear; but it may be directly connected, if desired.

The segmental rack E has a double flange e, which rests in a T-headed slot i in a segmental guideway I, having feet i' in the present instance, which are secured to the deck of the vessel. Detachable plates are provided, so that the segment can be removed, if desired. The rack is held in a central position 65 by spring-buffers K K, one at one end of the rack and the other at the opposite end. The rack is free to move to a limited extent in its guideways when the pressure upon it overcomes the springs of the buffers. Each 70 buffer consists of a casing L, an abutment-block J, and springs J'. In the present instance two coiled springs are mounted between the abutment-block and the end of the casing, although one spring may be used, if 75 desired. The abutment-block J is in line with the end of the segmental rack E, but is not connected to it, so that if the rack is forced in the direction of the arrow, for instance, Fig. 3, it will compress the springs, 80 and consequently move in its bearings to a certain extent, depending altogether on the tension of the springs, and it will be moved away from the buffer at the opposite end. If the direction is reversed, it will compress 85 the spring of the buffer at the opposite end and withdraw from the block J, Fig. 3. As soon as the pressure is reduced the segment will assume its normal position.

We preferably provide means for limiting 90 the movement of the block J and for adjusting the tension of the springs. In the present instance the block J has a screw-threaded opening, and extending through this opening is a threaded bolt J², having a head j at its 95 rear end. This bolt passes through a hollow screw-threaded bolt M, which is screwed into the casing L and has a jam-nut m. The bolt M bears against a collar M'. In order to take the strain off the bolt J², we prefer to secure 100

a cap-plate *l* to the front of the casing *L*, which overlaps a flange on the block *J*. In some instances the adjusting-bolts *J²* and *M* may be dispensed with without departing 5 from this feature of the invention. It will be seen, therefore, that if the pressure due to the waves striking the rudder causes a strain to be placed upon the rack-bar it will simply cushion against the block *J*, which will be 10 forced into its casing, compressing the springs and thus taking the shock and preventing the breaking of the pinion and the rack and relieving other parts of the mechanism from the severe strains or jars. The operation of 15 the apparatus is as follows: The valves of the engines are controlled by any suitable operating mechanism. If it is desired to move the tiller in one direction, the shaft *G* is turned and its motion will be imparted to 20 the shaft *C* through the bevel-gears *g* and *g'*, which in turn impart motion to the vertical shaft *d* through the worm and worm-gear. The pinion *d'* on the shaft meshes with the teeth of the rack, causing the tiller *D* to move 25 in the direction desired. If it is wished to hold the tiller in the adjusted position, the engines are stopped. If it is wished to reverse the direction of the tiller, the engines are reversed, when the tiller will move in the 30 opposite direction.

In some instances instead of mounting the buffers at each end of the segmental rack, as shown in Fig. 1, they may be mounted as shown in Fig. 4, and the projection on the 35 rear of the rack may extend between the two spring-abutments, as shown in said figure, or the abutments may be located at any point desired, the position depending upon the amount of room set apart for the steering- 40 gear.

In Fig. 5 we have shown a modification in which the shaft *C* is geared to a driving-shaft *G'* through an intermediate bevel-wheel *g*, mounted in line with the pivot of the tiller. 45

We claim as our invention—

1. The combination in a tiller steering-gear, of a tiller, a pivot therefor, a segmental rack, a pinion on the tiller engaging with the rack, and a stationary driving-engine, the 50 shaft of said engine being geared to the pinion, substantially as described.

2. The combination of a tiller, a pivot therefor, a pinion on said tiller, a rack engaged by the pinion, a driving engine or engines on 55 the fixed foundation, the driving-shaft of the engine being in line with the tiller-pivot, with means for gearing said driving-shaft to the pinion, substantially as described.

3. The combination of a tiller, a pivot therefor, a segmental rack, a pinion on the tiller 60 engaging with the rack, a driven shaft in line with the pivot, means for driving said shaft, a worm-shaft, bevel-gearing connecting the driven shaft to the worm-shaft, a worm on said worm-shaft, a shaft on which the pinion 65 is secured, and a worm-wheel on said shaft meshing with the worm, substantially as described.

4. The combination of a pivoted tiller, a shaft and a pinion carried by the tiller, a segmental rack with which the pinion engages, a fixed engine having a crank-shaft in line with the pivot of the tiller and gearing by which the said crank-shaft is geared to the pinion-shaft on the tiller, substantially as described. 70

5. The combination in a tiller steering-gear, of a tiller, a pinion on said tiller, means for driving the pinion, a segmental rack with which the pinion engages, with buffers controlling 80 the lateral movement of the rack, substantially as and for the purpose set forth.

6. The combination of a tiller, a pinion carried by the tiller, means for driving the pinion, a segmental rack with which the pinion 85 engages, guideways for said rack, with spring-buffers on each end of the rack but detached therefrom, whereby the rack will yield when under extreme pressure, substantially as described. 90

7. The combination of a tiller, a pinion carried by the tiller, means for driving the pinion, a rack with which the pinion engages, buffers for the rack, each buffer having a casing, a bearing-block within the casing, 95 springs between the bearing-block and the casing, and means for limiting the outward movement of the bearing-block, substantially as described.

8. The combination of a tiller, a pinion on the tiller, a rack with which the pinion engages, means for driving the said pinion, a buffer for the tiller, said buffer having a casing, a bearing-block, a spring or springs back of the bearing-block, means for adjusting the tension of the springs, and means for adjusting the bearing-block, substantially as described. 100

In testimony whereof we have signed our names to this specification in the presence of 110 two subscribing witnesses.
